TRACK RECORDER

Ernest A. Crawford, Cliffside Park, N. J., assignor
to Sperry Products, Inc., Hoboken, N. J., a cor-
poration of New York

Application June 7, 1947, Serial No. 753,347

6 Claims. (Cl. 116—124)

1

This invention relates to a railway track recorder mechanism and more particularly to a device for indicating the angle of inclination between a railway car body and the car axle. Such angle of inclination is a factor which it is highly desirable to know since it is an index of the proper banking of tracks around curves and also is an indication of the car body performance. These factors enter largely in providing safe travel, especially around curves. Various movements of the car body with respect to the axle 11 take place other than those resulting in relative inclination between the car body and the axle, such as, for example, car body bounce, rotation of the track unit about its center bearing when curves in the track are encountered, and shift of the car body in a horizontal plane. It is a further object of this invention to provide means which will indicate the inclination between the car body and the axle and which will not be affected by the hereinbefore mentioned movements so that such movements which do not result in relative angular inclination between the car body and the axle will not be indicated.

Further objects and advantages of this invention will become apparent in the following detailed description thereof.

In the accompanying drawings,

Fig. 1 is in part a front elevation partly sectioned vertically, and in part an isometric projection, of a portion of a railway car showing my invention applied thereto.

Fig. 2 is an enlarged view, mostly sectioned vertically, of the inclination responsive mechanism employed in Fig. 1.

Referring to the drawings there is shown a portion of a car body 10 having an axle 11 and flange wheels 12 adapted to ride on the rails of a railway track. The various conventional mechanisms by which the car body is supported on the trucks, of which only the axle 11 is shown, have been omitted. It is desired as stated in the introduction hereto to indicate any out of parallelism between the axis of axle 11 and the horizontal base of the car body which results in tilting of the car body particularly when travelling around curves.

It is a further purpose of this invention to provide such mechanism which will not be affected by relative movements between the car body and the axle which do not result in change

in angular relationship between the car body and the axle.

To accomplish the above purpose I provide two hydraulic elements indicated generally at 20 and 20' which are connected by suitable connectors 21 and 21' to the underside of the car body. The hydraulic elements 20 and 20' each comprises a cylinder 22, 22' and a piston 23, 23'. In hydraulic element 20 the cylinder 22 is fixedly connected to the fixture 21 while in hydraulic element 20' the piston 23' is fixedly connected to the fixture 21'. The fixture 21 is provided with a bore 24 communicating through pipe 25 with a bore 24' in fixture 21'. The bore 24 communicates adjacent its lower end with passages 26 whereby the bore 24' communicates with the interior of cylinder 22'. The piston 23 is movable within the fixed cylinder 22 and is connected at its lower end by a fixture 30 to one end of the axle. The movable cylinder 22' sliding on the fixed piston 23' is connected through a fixture 30' to the other end of axle 11.

Two fluid chambers 31 and 31' are thus formed in the cylinders 22 and 22' respectively. Downward movement of axle 11 parallel to the car body floor will result in piston 23 being drawn downwardly to enlarge the volume of chamber 31, while cylinder 22' is drawn downwardly to diminish the volume of chamber 31'. If the two cylinders are so designed that the area of piston 23' minus the area of fixture 21' equals the area of piston 23, and if the chambers and the connecting passages of transmission system 24, 25 and 24' are maintained filled with fluid, then such movement will merely result in the transfer of liquid through the system without diminishing or increasing the total fluid volume of the system. Similarly upward movement of axle 11 parallel to the car body floor will result in piston 23 being moved upwardly to diminish the volume of chamber 31, while cylinder 22' is moved upwardly to increase the volume of chamber 31'. This will be the condition whenever there is car bounce, or when there is rotation of the truck unit about its center bearing when curves in the track are encountered, without resultant inclination of the car body with respect to the axle, or when the car body shifts in a horizontal plane.

If, however, the axle tilts with respect to the car body in such manner, for example, that piston 23 is drawn downwardly to increase the volume of chamber 31, and cylinder 22' is moved up-

wardly to increase the volume of chamber 31', then it will be seen that the total volume of the transmission system (consisting of chamber 31, passageways 24, 25, 24', 26 and chamber 31') has been increased. A connection 35 leads from the transmission system to a reservoir 36 having a chamber 37 filled with fluid and under pressure by spring 38 pressing upon piston 39. As the fluid volume of the transmission system enlarges due to the inclination of the axle relative to the car body, piston 39 will be moved to the right in Fig. 1 to supply more fluid to the system. Such movement of the piston may be indicated by any suitable indicator such as a pen P operating on a moving chart C normally to draw a straight line as shown at 40 but when the piston moves in response to changes of fluid requirements in the transmission system offsets such as shown at 41 are made by the pen.

If the angle of inclination is in the opposite direction with respect to the car body so as to move piston 23 upwardly to diminish the volume of fluid chamber 21 and cylinder 22' is moved downwardly to diminish the volume of fluid chamber 31', the total fluid volume of the transmission system will be diminished and fluid will be forced through pipe 35 into chamber 37 of reservoir 36, to move piston 39 to the left and cause pen P to indicate an offset, as shown at 42, on the opposite side of line 40.

It will thus be seen that only relative inclination between the car body and the axle will result in movement of fluid into or out of the transmission system 22, 24, 25, 24', 22' and hence actuation of the indicating mechanism. Other movements, such as car bounce, horizontal shift of the car body or rotation of the car body around the truck axis will merely transfer fluid from one side of the transmission system to the other without increasing or diminishing the fluid volume of the system and hence without adding to or subtracting from the fluid in the system. Therefore, only relative inclination between the car body and the axle will be indicated.

Having described my invention, what I claim and desire to secure by Letters Patent is:

1. A device for indicating relative tilt between a car body and the car axle, comprising a hydraulic system including a pair of spaced, communicating hydraulic elements between the car body and the axle, each element comprising a cylinder and a piston therein to form a fluid chamber, the piston of one element and the cylinder of the second element being connected to the car body to move therewith, and the cylinder of the first element and the piston of the second element being connected to the axle to move therewith.

2. A device for indicating relative tilt between a car body and the car axle, comprising a hydraulic system including a pair of spaced, communicating hydraulic elements between the car body and the axle, each element comprising a cylinder and a piston therein to form a fluid chamber, the piston of one element and the cylinder of the second element being connected to the car body to move therewith, the cylinder of the first element and the piston of the second element being connected to the axle to move therewith, and a reservoir for supplying liquid to said system when the total capacity of the chambers increases and for receiving liquid from said system when the total capacity of the chambers decreases.

3. A device for indicating relative tilt between a car body and the car axle, comprising a hydraulic system including a pair of spaced, communicating hydraulic elements between the car body and the axle, each element comprising a cylinder and a piston therein to form a fluid chamber, the piston of one element and the cylinder of the second element being connected to the car body to move therewith, the cylinder of the first element and the piston of the second element being connected to the axle to move therewith, a reservoir for supplying liquid to said system when the total capacity of the chambers increases and for receiving liquid from said system when the total capacity of the chambers decreases, and indicating means actuated in response to the supply of fluid in said system.

4. A device for indicating relative tilt between a car body and the car axle, comprising a hydraulic system including a pair of spaced, communicating hydraulic elements between the car body and the axle, each element comprising a cylinder and a piston therein to form a fluid chamber, the piston of one element and the cylinder of the second element being connected to the car body to move therewith, the cylinder of the first element and the piston of the second element being connected to the axle to move therewith, a reservoir for supplying liquid to said system when the total capacity of the chambers increases and for receiving liquid from said system when the total capacity of the chambers decreases, and indicating means actuated in response to the supply of liquid in the reservoir.

5. A device for indicating relative tilt between a car body and the car axle, comprising a hydraulic system including a pair of spaced, communicating hydraulic elements between the car body and the axle, each element comprising a cylinder and a piston therein to form a fluid chamber, the piston of one element and the cylinder of the second element being connected to the car body to move therewith, the cylinder of the first element and the piston of the second element being connected to the axle to move therewith, and indicating means actuated in response to the differential movement of the members movable with the axle.

6. A device for indicating relative tilt between a car body and the car axle, comprising a hydraulic system including a pair of spaced, communicating hydraulic elements between the car body and the axle, each element comprising a cylinder and a piston therein to form a fluid chamber, the piston of one element and the cylinder of the second element being connected to the car body to move therewith, the cylinder of the first element and the piston of the second element being connected to the axle to move therewith, and indicating means actuated in response to the differential expansion and contraction of the fluid chambers of said cylinders.
